CLAIM

The ornamental design for a car tire, as shown and described.

DESCRIPTION

FIG. 1 is a front view of a first embodiment of the tire, it being understood that the tread pattern is repeated throughout the circumference of the tire;

FIG. 2 is a left side view of the first embodiment of the tire;

FIG. 3 is a perspective view of the first embodiment of the tire;

FIG. 4 is a right side view of the first embodiment of the tire; FIG. 5 is an enlarged view of FIG. 1, showing a portion thereof;

FIG. 6 is a front view of a second embodiment of the tire, it being understood that the tread pattern is repeated throughout the circumference of the tire;

FIG. 7 is a left side view of the second embodiment of the tire;

FIG. 8 is a perspective view of the second embodiment of the tire;

FIG. 9 is a right side view of the second embodiment of the tire; and,

FIG. 10 is an enlarged view of FIG. 1, showing a portion thereof.

The portions of the tire depicted in broken dashed lines of uneven length mark the boundaries of the claimed design. The portions depicted in broken dashed lines of even length illustrate portions of the tire that form no part of the claimed design. The broken dashed lines of even length that form a box in each of FIGS. 1, 5, 6, and 10 illustrate the boundary of the enlarged portion of the front views and form no part of the claimed design.

1 Claim, 10 Drawing Sheets
